UNITED STATES PATENT OFFICE.

CLIFFORD C. BRADBURY, OF OAK PARK, ILLINOIS, ASSIGNOR OF ONE-HALF TO
ROBERT F. BRACKE, OF CHICAGO, ILLINOIS.

TOY RAILROAD SYSTEM.

Application filed September 25, 1922. Serial No. 590,251.

To all whom it may concern:

Be it known that I, CLIFFORD C. BRADBURY, a citizen of the United States, and resident of Oak Park, in the county of Cook 5 and State of Illinois, have invented a certain new and useful Improvement in Toy Railroad Systems, of which the following is a full, clear, concise, and exact description, reference being had to the accompanying 10 drawings, forming a part of this specification.

My invention relates to toy railroad systems, and more especially, although not necessarily, to such inexpensive trains as are 15 propelled manually rather than by spring or electric motors and which have no tracks and flanged wheels to prevent lateral displacement of the train.

One object of my invention is the provision 20 of a toy train system in which the train runs upon a painted track and is guided by the co-operation of guides secured to the cars of the train with a groove running along the track whereby substantially the same enjoyment is had by a child operating the train 25 as though the train ran upon a real track and wherein the expense of manufacture is nominal compared with the manufacture of a real track.

Another object of my invention is to provide 30 a simple, inexpensive and efficient means for guiding a toy train around a predetermined pathway.

A further object of my invention is the 35 provision of a toy railway system in which the toy train runs about a tray which may be inexpensively manufactured either by stamping it from a single sheet of metal or by molding celluloid in a thin sheet-like 40 tray.

Still another object is the provision of an 45 inexpensive toy train system which may easily be rested on the knees of the child who plays with it or may be used by a child in a sick bed without the inconvenience of the train being easily run off or dropped from the tray upon which it rests.

Many other features and advantages of 50 my invention will become apparent in the reading of the following description, in which I refer to the accompanying drawings which illustrate an adaptation of my invention and wherein:

Figure 1 is a plan view of the tray with 55 a toy train thereon;

Figure 2 is a vertical section taken on the line 2-2 of Figure 1;

Figure 3 is an enlarged vertical section taken longitudinally of the train on the line 3-3 of Figure 1;

Figure 4 is a transverse vertical section of the train and tray taken on the line 4-4 of Figure 3; and

Figure 5 is a detail plan of a portion of the tray showing the printed trackway, 65 switches and the like with which the upper surface of the tray is preferably provided, but which has been omitted from Figure 1 for convenience and clarity.

Similar reference characters refer to similar parts throughout the several drawings.

The tray 10 which forms the surface upon which the train 11 runs is preferably made from a sheet of thin material and provided adjacent its margin with a rather deep 75 groove 12, and at its margin with an upturned flange 13 which forms a side for the tray of sufficient height to prevent the train, should it leave its guiding groove, from falling off the tray. The groove 12 and flange 13 80 also serve effectively to reinforce the thin sheet to make the tray quite rigid. The bottom of the tray is provided with a plurality of connected grooves 14 preferably arranged with the conventional switches, curves, figures 85 and spurs with which the track of a toy railway system is customarily provided.

While these grooves 14 may be provided on a tray of any construction and of comparatively great thickness, they are especially adapted to a tray which is formed from sheet-like material, such as sheet metal, in which case the trays may be stamped in large quantities from dies at a very low 90 cost per tray. My invention is also particularly suitable in its application to a tray support molded from celluloid or similar substance in which the celluloid can be formed in a very thin sheet which will still 95 retain sufficient rigidity because of the reinforcing effects of the grooves 14, as well as the marginal flanges.

The toy train 11 is preferably composed of the conventional locomotive, tender and other cars which are provided with the usual transversely spaced supporting wheels 15 which actually rotate upon axles, although if a cheaper construction be preferred, the "dummy" supporting wheels may 100 110

be provided. The several cars may be coupled together in any suitable manner, such as by the overlapping lugs 16 provided respectively with the usual hook and eye 5 construction.

Spaced preferably midway between the supporting wheels is a guide member 17 which comprises a small rod extending downwardly from each car below the plane 10 of the surface of the tray and into the groove 14, where it is provided with an offset hook-shaped portion 18 lying in a vertical plane longitudinally of the car. The hook-shaped offset 18 prevents any sharp edges of the 15 guide member from digging into the sides of the co-operating groove 14 and also prevents the guide member from continuing in the wrong groove when passing the cross-overs 20 in the circuitous groove 14. In the drawings the cars illustrated are die cast and the guide member 17 has been die cast into the bottom of each car and is preferably surrounded at its attachment to the car by a reinforcing boss 21. It will be understood, however, that in cars which are stamped from sheet metal, or otherwise constructed, equally satisfactory methods of supporting the guide member 17 may be devised and that the guide member itself may 25 take a number of other but suitable forms.

The toy train will operate successfully whether each guide member 17 is placed at the end or at the middle of its car, but as a centrally located guide member tends to permit a swinging of the car, and especially of an end car, I prefer to locate the guide members well toward the rear of each car, and as here shown, near the axis of the supporting wheels, whereby the latter serve to hide 30 the guide members from view. When the guide members are thus located at the rear of each car, the forward car—in the drawing, the locomotive—is provided with an auxiliary guide member 17' at its forward 35 end, as there is no car ahead of this to guide the forward end of the locomotive. Conversely, if the guide member is placed at the forward end of each car, the last car, or 40 caboose, is preferably provided with a guide member at each end.

It is to be observed that the tangential relation of the grooves at the switches 19 is such that the pulling on the forward car 45 will result in a sufficient transverse component at the switches to cause the successive guides 17 to follow which ever groove the first car has entered.

By the imprinting, decalcomania, or other simulation of a railroad track 22 with its rails, ties, switches 23 and the like, provided at the upper surface of the tray 10 and following the grooves 14, the train will run on this track in a realistic manner, as the supporting wheels 15 will travel quite accurately along the simulated rails of the 50

track 22. As shown in Figure 5, the track is so imprinted that the groove 14 falls midway between the rails, so that the co-operating guide 17, which is midway between the supporting wheels 15, positions 70 the latter upon the rails of the track. In this manner, and for very little cost of manufacture, a realistic result is easily accomplished without the use of raised rails or even wheels that actually rotate. It is 75 also to be observed from Figure 5 that stations 24, switch-stands 25, water tanks 26 and the like can also be printed upon the tray at little additional expense.

While I have illustrated but a particular 80 adaptation of my invention, it is to be understood, of course, that many changes therein may be made without departing from the spirit of my invention, which is to be limited only by the prior art and scope of the appended claims.

I claim:

1. A toy railroad system comprising in combination a thin sheet-like tray having upturned margins, a groove generally U-shaped in cross section formed in said tray and having curves and switches, a plurality of cars forming a train, each car having supporting wheel members resting upon said tray adjacent to said groove, a guide secured 90 to each of said cars and extending into said groove and guiding said train.

2. A toy railroad system comprising in combination a base and a train of cars reciprocable upon said base, each car being provided with one, and one end car with two, guide members secured near the ends of their respective cars, and a grooved guideway in said base, said guides extending into 100 said guideway.

3. In combination, a toy railroad train consisting of a plurality of cars having transversely spaced supports, guide means between said supports and extending below the plane of said supports, a sheet metal 110 tray upon the upper surface of which said supports slidably rest, and a circuitous groove substantially U-shaped in cross section in said surface in which said guide means travels for preventing transverse 115 movement of the cars.

4. A toy train system comprising a train of cars and a base portion upon which said train runs, supporting wheels on each car for slidably supporting said car upon said base, a circuitous groove in said base, and a rod depending from each said car and at its bottom being offset longitudinally of the car, said offset extending into said groove, with which it co-operates to guide said car along 120 the path of said groove, said offset being freely removable from said groove.

5. In a toy adapted to be held upon the knees of the operator, the combination with a toy car of a tray upon which said car 125

runs, said tray being formed of an imperforate sheet of material and having a groove extending adjacent its margin and having an upturned flange at its margin for retaining said car within said tray, a groove substantially U-shaped in cross section on the bottom of said tray, and a guide on said car co-operating with said groove to guide said car.

13 6. A toy railroad system comprising a thin sheet metal tray having an up-turned marginal flange and provided with a circular groove or depression in the upper face thereof, said groove being substantially U-shaped

in cross-section, a plurality of cars having 15 transversely spaced supports and guide means carried by said cars between said supports and extending below the plane thereof and into said grooves, said marginal flange and groove acting to give rigidity to said tray.

In witness whereof, I hereunto subscribe my name this 21 day of September, 1922.

CLIFFORD C. BRADBURY,

Witnesses:

DAGMAR PETERSON,
EDNA U. GUSTAFSON.
